UNITED STATES PATENT OFFICE

JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA

CORE-MAKING APPARATUS

Application filed March 6, 1928. Serial No. 259,529.

This invention relates to core making apparatus, and among other objects, aims to provide apparatus of this character which is peculiarly suited to the continuous and large 5 scale production of cast iron pipe, being so built that the core bars may be moved through the machine in one direction.

In the accompanying drawings showing a preferred embodiment of the invention:

10 Fig. 1 is an elevation of a core making apparatus, showing the pit for the sand in section; and

Fig. 2 is a side elevation of the same, showing the pit in cross-section.

15 Apparatus for making green sand cores for use in casting pipes have been in use for many years. In these, the sand is dropped through a chute onto the core bar while it is revolving. The core knife cuts off the excess sand, leaving the core the exact size required. However, with the usual type of green sand core apparatus it is impossible to put the core bars in on one side and take them 20 out on the other. For the purpose of continuous operation, it is very desirable to keep the cores going in one general direction, avoiding the loss of time and labor which is necessarily involved when the cores are moved 25 into and out of the apparatus on one side.

30 The purpose of this invention is to provide an apparatus making possible movement of the cores in one direction. Apparatus embodying the invention forms a useful element in a pipe foundry such as is described and claimed 35 in my application, Serial No. 220,731, filed September 20, 1927.

40 Referring further to the drawings, there is shown a core making apparatus comprising a frame, a sand handling mechanism for delivering green sand to points above the core bar, a sand delivering member, and a rotary core bar support beneath the sand delivering member. As disclosed in the aforesaid application, the apparatus is located between the 45 core bar reconditioning zone, and the assembling zone, where the core bars are assembled with the flask sections, and is open on one side to the runs or rails which are conveniently used to carry the core bars, and is open on the other 50 side to that part of the plant where the core

bar carrying crane travels. The apparatus is so built as to permit uni-directional movement of the core bars therethrough, the core bars being moved laterally into the position where green sand is distributed over them, and being moved laterally after the cores are formed thereon in the same direction to a position upon a core bar support such as is described 55 in my application, Ser. No. 257,708, filed February 28, 1928.

60 The frame shown in the drawings comprises columns 5, beams 6 supported by the columns and braced by lattice bars 7, and the necessary angle plates and crosspieces for supporting the motors and other parts without destructive vibration. The columns 5 are at the opposite ends of the machine, and the beams 6 are high overhead, so that a clear 65 space through the machine is provided for travel of the core bars laterally. A core bar 70 8 is shown in Figs. 1 and 2 as resting on a rotary support 9 such as the one described and claimed in my application entitled "Core bar supports" filed August 30, 1927, Serial No. 216,467. Cross beams 10 extend above 75 the rotary support 9 and carry standard pneumatic or electric hoists (not shown) which are provided with members to fit in the two ends of the core bars to pick them up and convey them laterally toward and away 80 from the core bar supports 9, moving them always in one direction. If desired, there may be four such hoists, two on each beam 10, permitting one pair to be used for conveying the core bars into core-forming position, and 85 the other pair for conveying cores onto the support previously mentioned.

90 To elevate the green sand to a level well above the core bars, so that it may be distributed as uniformly as possible over the entire length thereof, and also to recover the green sand which does not cling to the core bar but falls below, there is a flight conveyor 11 driven by a motor 12 supported on beams 6. For convenience of illustration, the flight 95 conveyor is shown rather diagrammatically, as its exact construction is of no consequence, so far as this application is concerned. The lower run of the flight conveyor travels in a pit 13 which extends the 100

length of the machine underneath the core bar supports 9 and which receives through a grating 14 the green sand falling off the core bar during formation of the core. The upper run of the flight conveyor travels in a kind of a trough 15 extending the greater part of the length of the apparatus having an opening or series of openings (not shown) in the bottom thereof for distributing the sand as uniformly as possible into a chute 16 whose lower end tapers and terminates a short distance above the core bar, as shown. Preferably the chute 16 is vibrated, as by a motor 17, when sand is being delivered to the core bar, and means may also be provided to shut off flow of the sand when desired. Such details are not described at length here, nor shown clearly in the drawings, because they form no part of the present invention. A fresh supply of sand is delivered to the flight conveyor preferably at one end of the apparatus, and is brought to the apparatus by means of a belt chute or the like (not shown), according to the layout of the plant.

It will be clear that instead of using a single conveyor, as shown, three or four separate conveyors may be used to do the same work, namely, one in the pit, one at either end of the pit and rising vertically, and one at the top of the apparatus. Any conveyor arrangement which will recover the sand from below the core bar supports and convey an adequate supply of it to such an elevation as to permit distribution upon the rotating core bar, but which affords a clear space through the apparatus for uni-directional movement of the core bars, is deemed to be within the scope of the present invention.

Obviously the invention may be embodied in other forms.

What is claimed is:—

1. Core making apparatus comprising, in combination, an open frame; a sand elevator on the frame; said frame, because of said opening, being constructed and arranged for receiving the core bars on one side and for taking the completed cores out on the opposite side, and the sand elevator being located to one side, out of the way, thus making possible the movement of the core bars through the apparatus without retracting the path of movement into the apparatus.

2. Core making apparatus having an open frame providing a passageway permitting lateral movement of the core bars therethrough; and means for distributing sand upon core bars when supported in the passageway; the apparatus permitting movement of the core bars therethrough without interference with the movement of other core bars as they are brought up to the apparatus.

3. Core making apparatus comprising, in combination, an open frame; a conveyor for carrying core sand to the upper part of the frame; said conveyor operating in a vertical

plane which is approximately at right angles to the direction in which the core bars move; the apparatus being sufficiently open to permit passage of the core bars in one direction through the apparatus; and means for distributing the core sand which is lifted by the conveyor over the surfaces of the core bars.

4. Core making apparatus comprising, in combination, an open frame; a conveyor for carrying core sand to the upper part of the frame; said conveyor operating in a vertical plane which is approximately at right angles to the direction in which the core bars move; said conveyor being continuous and running over the top of the apparatus to deliver the core sand above the core bars, and passing beneath the core bars to collect the core sand which falls below them; the apparatus being sufficiently open to permit passage of the core bars in one direction through the apparatus; and means for distributing the core sand, which is lifted by the conveyor, over the surfaces of the core bars.

5. Core making apparatus comprising, in combination, an open frame; a conveyor for carrying core sand to the upper part of the frame; the apparatus being sufficiently open to permit passage of the core bars in one direction through the apparatus; a core bar support located in the passageway in the apparatus; a pair of horizontal beams at each side of and above the passageway to support core bar handling means and permit travel thereof with a core bar through the opening in the frame; and means for distributing the core sand, which is lifted by the conveyor, over the surfaces of the core bar.

In testimony, that I claim the foregoing as my own, I have hereto affixed my signature.

JAMES R. McWANE.
